U.S. Appl. No. 29/677,450, filed Jan. 21, 2019, Liao.

U.S. Appl. No. 29/692,070, filed May 22, 2019, Liao.

Primary Examiner — Cynthia Ramirez*(74) Attorney, Agent, or Firm* — Daniel F. Nesbitt; Hasse & Nesbitt LLC(57) **CLAIM**

I claim the ornamental design for a trash can, as shown and described.

DESCRIPTION

FIG. 1 is a top, front, right-side perspective view of the trash can, showing my new design;

FIG. 2 is a top, back, left-side perspective view of the trash can;

FIG. 3 is a front view of the trash can;

FIG. 4 is a back view of the trash can;

FIG. 5 is a right side view of the trash can;

FIG. 6 is a left side view of the trash can;

FIG. 7 is a top view of the trash can; and,

FIG. 8 is a bottom view of the trash can.

The broken lines in the figures are for the purpose of illustrating portions of the trash can, which form no part of the claimed design.

1 Claim, 8 Drawing Sheets
